UNITED STATES PATENT OFFICE.

ALBERT A. DENTON, OF EAGLE RIVER, WISCONSIN.

WOOD-DRYING MACHINE.

1,274,860.

Specification of Letters Patent.

Patented Aug. 6, 1918.

Application filed February 10, 1917. Serial No. 147,841.

To all whom it may concern:

Be it known that I, ALBERT A. DENTON, a citizen of the United States, residing at Eagle River, in the county of Vilas and 5 State of Wisconsin, have invented certain new and useful Improvements in Wood-Drying Machines, of which the following is a specification.

This invention relates to a wood drying 10 machine and the primary object of the invention is to provide a device for thoroughly drying chips of wood preparatory to the process of converting them into paper pulp.

15 One of the objects of the invention is to provide a series of interconnected cylinders to which the chips are passed while the device is in operation, the cylinders being associated with a heating element so that 20 the interiors of the cylinders will thoroughly agitate and dry the chips while they are passing through the cylinders.

Another object of the invention is to provide a series of cylinders adapted to receive 25 the chips, the cylinders being exteriorly heated and associated with interior screw conveyers mounted upon hollow shafts through which steam may be passed for heating the conveyers and the interiors of 30 the cylinders.

A further object of this invention is the provision of a wood drying machine which consists of comparatively few parts and is simple in construction, but durable and 35 well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a side elevation of the device 45 showing parts of the cylinders broken away to disclose the interior.

Fig. 2 is an end elevation.

Fig. 3 is a detail section through one of the cylinders.

50 Referring to the drawing, wherein is illustrated the preferred form of my invention, and in which like numerals of reference indicate corresponding parts throughout the several views, it will be observed 55 that the drying device is arranged in close proximity to the chipping machine A only

a portion of which is shown in the drawing. Any suitable conveyer B is arranged for receiving the chips from the chipping machine A so that the chips may be elevated to a sufficient height whereby they may be received in the drying machine. End standards 1 and 2 are provided with suitable bearings for receiving the ends of the shafts 3, 4 and 5. Each shaft is provided with a screw conveyer 6 for conveying the chips through the cylinders from one end to the other. Three cylinders 7, 8 and 9 are mounted upon the shafts 3, 4 and 5 respectively. The interior diameter 70 of each cylinder is slightly greater than the diameter of the screw conveyer within the cylinder. Each open end of each cylinder is provided with spokes 10 for supporting the cylinder on its corresponding 75 shaft. The cylinders, hollow shafts and screw conveyers revolve simultaneously when the cylinders are rotated since the shafts are connected to the cylinders by the spokes 10 at each end thereof. Mounted 80 upon the exterior of each cylinder at one end thereof is a gear 11 and the teeth of these gears are in mesh with each other so that when a rotary motion is imparted to one of the cylinders all of the cylinders 85 will be rotated.

Steam pipes 12 having their free ends closed are extended through the longitudinal space provided between the cylinders and these pipes are connected to a supply 90 pipe 13 so that steam may be supplied to the pipes 12 for heating the cylinders. The free ends of the pipes 12 are capped as indicated at 12' in Fig. 1. In this connection it is pointed out that any other suitable heating element may be employed for 95 heating the cylinders.

The upper cylinder 7 and the intermediate cylinder 8 are interconnected at their ends by a conveying duct 14. The opposite end of the intermediate cylinder 8 is connected to the corresponding end of the lowermost cylinder 9 by a conveying duct 15. These conveying ducts 14 and 15 are connected to and supported by the end 100 standards 1 and 2 through the medium of supporting straps 14' and 15' and have their ends in registration with the ends of the cylinders but are not connected thereto. This permits the cylinders to revolve while 105 discharged chips from the cylinders may pass into the stationary ducts as the chips 110

are conveyed from one end of the cylinders to the other. The connection of the hollow shafts 3, 4 and 5 with the supporting standard is such as to permit open communication 5 of the interior of the shafts with steam conveying pipes while permitting the shafts, at the same time, to revolve when the cylinders are rotated.

A plurality of longitudinally extending 10 cleats 16 are mounted upon the inner wall of each cylinder as clearly shown by Fig. 3 of the drawing. These cleats engage the chips and are intended to toss the chips about within the cylinder so that they will 15 be thoroughly agitated for facilitating the drying process. While the cleats are agitating the chips within the cylinders, the conveyer screws will also be operating to convey the chips from one end of each cylinder to the other. 20

It is to be noted that each shaft 3, 4 and 5 is hollow and the terminals thereof are projected beyond the standards in which they are mounted. A steam pipe 17 is connected to one end of the hollow shaft 3 and this steam pipe supplies the interior of the shaft with steam so that the screw conveyer 6 within the cylinder 7 is thoroughly heated for assisting in the drying process while 25 the chips are passing through the cylinder. At the opposite end of both of the shafts 3 and 4, suitable elbow fittings are secured and these elbows are connected together by a connecting pipe 18 which serves to conduct 30 the steam from the interior of the shaft 3 and the interior of the shaft 4 thereby heating the screw conveyer within the cylinder 8. The opposite end of the hollow shaft 4 is connected, through the medium of a connecting pipe 19, with the corresponding end 35 of the hollow shaft 5. The steam is permitted to escape from the opposite end of the hollow shaft 5 through a suitable exhaust pipe 20.

40 In operation it is first necessary to elevate the chips through the medium of a suitable elevator B until the chips can be deposited in one end of the uppermost cylinder 7. While the cylinders are in operation the 45 chips will be removed from one end of the uppermost cylinder to the other end thereof and conveyed through the conveyer duct 14 to the intermediate cylinder 8. After passing through this cylinder the chips will 50 pass into the lowermost cylinder 9 through the medium of the conveying duct 15. From the lowermost cylinder 9 the dried chips may be deposited in a suitable receiver C. The steam pipes 12 will, while the cylinders 55 are rotating be subjected to the action of the steam, and the cylinders are thereby thoroughly heated from the exterior for facilitating the drying process. The conveyers 6 are heated by the steam which passes 60 through the hollow shafts upon which the 65

conveyers are mounted. This steam will heat the shafts in addition to heating the portions of the conveyer with which the chips contact while passing through the cylinders. In this manner heat is supplied 70 from the interior and the exterior thereby quickly drying the chips. When the chips are ejected from the lowermost cylinder and deposited in the conveyer C they will be thoroughly dried and ready to be converted 75 into pulp.

From the foregoing it will be observed that a very simple and durable wood drying machine has been provided, the details of which embody the preferred form. I desire 80 it to be understood however, that slight changes in the minor details of construction may be made without departing from the spirit of the invention or the scope of the claims hereunto appended. 85

I claim:

1. A drying machine of the character described comprising a plurality of cylinders having centrally located hollow shafts extending therethrough, gearing mechanism 90 associated with the cylinders for simultaneously rotating the same, the said shafts being rotatable with the cylinders, screw conveyers mounted upon the said shafts, steam pipes connected to the ends of the shafts for 95 providing a continuous circuit through the steam pipes and the hollow shafts and means for permitting the contents of one cylinder to pass out of the end of the other cylinder into the proximate end of the adjacent cylinder. 100

2. A drying machine of the character described comprising standards, a plurality of hollow shafts having their ends supported by the standards, a cylinder having a hollow 105 interior and mounted upon each shaft, a plurality of ducts connecting the open ends of the cylinders for permitting the contents thereof to pass from one cylinder to another, while the cylinders are being rotated, and means for rotating the cylinders, certain of the ends of the said shafts being connected together to establish a continuous circuit of hollow members through the said cylinders. 110

3. A drying machine comprising a plurality of cylinders having hollow interiors and provided with shafts extending beyond the open ends of the cylinders, standards receiving the ends of the shafts for supporting the same, conveyer screws mounted upon 115 each of the said shafts, the interior diameter of each cylinder being slightly greater than the diameter of the said screw conveyer, and a plurality of cleats carried by the inner wall of each cylinder. 120

4. A drying machine comprising a plurality of cylinders having hollow interiors and provided with shafts extending beyond the open ends of the cylinders, standards receiving the ends of the shafts for support- 125 130

ing the same, conveyer screws mounted upon each of the said shafts, the interior diameter of each cylinder being slightly greater than the diameter of the said screw conveyer, a 5 plurality of cleats carried by the inner wall of each cylinder, the said shafts being of hollow cylindrical formation, connecting pipes for joining the proximate ends of certain of the said shafts whereby a continuous 10 passage may be established between the

hollow shafts and the said pipes, and a steam supply pipe connected to one end of one of the said shafts.

In testimony whereof I affix my signature in presence of two witnesses.

ALBERT A. DENTON.
